UNITED STATES PATENT OFFICE.

GUSTAVE W. HAAS, OF LOS ANGELES, CALIFORNIA, ASSIGNOR OF ONE-HALF TO MARGARET B. FOWLER, OF PASADENA, CALIFORNIA.

ORTHOPEDIC OPERATING-TABLE.

No. 885,243.

Specification of Letters Patent. Patented April 21, 1908.

Application filed December 27, 1907. Serial No. 408,264.

To all whom it may concern:

Be it known that I, GUSTAVE W. HAAS, a citizen of the United States, residing at Los Angeles, in the county of Los Angeles and State of California, have invented certain new and useful Improvements in Orthopedic Operating-Tables; and I do hereby declare the following to be a full, clear, and exact description of the same, reference being had to the accompanying drawings, forming a part of this specification, and to the figures and letters of reference marked thereon.

The object of this invention is to provide a table or table like apparatus for use in orthopedic treatment of various kinds of deformities whereby with a single apparatus, practically all kinds of deformities may be correctively treated with the least possible inconvenience to the patients.

The invention consists primarily in a table like support upon which the patient may rest in a reclining position and around which is erected a superstructure the component parts of which superstructure are adjustable with relation to each other and are adapted to form the support for tractor connections and by reason of their adjustability permit of the extension of the tractor connections in any desired direction.

Referring to the accompanying drawings— Figure 1 is a perspective view of an operating table embodying the present improvements and showing several appliances adapted for use in connection therewith. Fig. 2 is also a perspective view looking at one end.

Like letters of reference in the several figures indicate the same parts.

The base or pedestal of the table is preferably formed with tubular side bars A from which rigid legs A' extend downwardly at four points sufficiently near the corners to prevent any possibility of the table upsetting by weight applied to its upper side, and at the same time sufficiently far within the corners to avoid interference with the operator's feet when standing close to the table. The pedestal frame is preferably provided with a centrally arranged board or support A² which not only braces the structure, but constitutes a convenient receiver for any of the detached parts of the superstructure, or for the attendant's instruments should any be used. The side frames A are curved upwardly at the ends and support the table or bed proper, lettered B. The latter it will be understood

is preferably somewhat in the form of a couch and is padded or covered with an agreeably soft but non-absorbent covering such as leatheroid or similar substance. The table forms an extended plane upon which the body of the patient may rest in reclining position, and a series of pads or cushions of various shapes are provided for giving corrective pressure upon various parts of the anatomy.

As shown in the drawings, a round pillow or support C is at one end of the table, and immediately adjacent thereto are two semi-cylindrical pads or supports C² and C³ respectively, one being of large and the other of smaller size. For supporting portions of the body against lateral movement, or for imparting lateral pressure, relatively short wedge shaped pads or cushions C⁴ are provided, these cushions being preferably arranged in pairs so as to form a trough like space between them in which the body of the patient may rest with the maximum comfort while undergoing treatment. In addition, a wide wedge shaped cushion C⁵ is provided upon which the body or legs of the patient may be raised to an inclined position.

The superstructure hereinbefore referred to embodies a series of vertical posts D at the corners and intermediate posts D', said posts being preferably detachably secured in the body of the table by screw thread connections whereby any one or more of them may be removed should occasion require. Each post is provided with a removable cap d which when removed as shown at the center of Fig. 1, leaves the post in the form of a socket adapted to receive an extension E to which tractor connections may be made as will be readily understood.

In addition, each post is provided with vertically adjustable rail or horizontal bar clamps F, each adapted to be held in its adjusted position by a set screw f and each adapted to receive the end or ends of horizontal rails or bars H, the bars themselves being adjustably held in position by set screws f'. With this arrangement a superstructure may be erected entirely around the table and this superstructure conveniently forms the base for the attachment of various extensions to which traction devices may be connected. In addition, each rail is adapted to carry any desired number of adjustable clamp hooks I, the hook members of which are preferably formed by screws i whereby

when engaged with a brace or traction member, the engagement will be permanent until the screw is backed out, thereby eliminating danger of accidental release while the patient is undergoing treatment.

As shown in the drawings, the superstructure is adapted at the head end to carry an upwardly projecting frame embodying front and rear standards K and K' connected at their lower ends by hinge joints with clamps k adjustably mounted on the rails or rods H. The standards K and K' converge toward their upper ends where they are connected together and to a cross bar K² extending across the table from side to side. Lateral movement of the frame may be prevented, first by extending one of the standards at each side, outside of the upper rail H and connecting it to the lower rail, whereby the upper rail will form a brace, although it is preferred, especially where the frame is erected at one end of the table to employ diagonal braces K³ to the head rail H, as shown clearly in Fig. 2.

The cross bar K² serves as a most convenient support for head and shoulder tractor slings, thus the head sling L is suspended by flexible connections l from the ends of the cross bar K² while the shoulder slings L' are suspended by flexible connections l' from the central portion of the bar K², but it will be understood that these tractor devices or others of any suitable nature may be connected with the rails or rods at any point and that by reason of the universal adjustability of the connections, the support for the tractor connections may be braced to resist any strain which it would be practical to employ in connection with orthopedic treatment. In all of the tractor devices or connections, it is preferred that spring balance scales such as indicated at L² should be employed and that the flexible connections should embody the capacity for ready adjustment, such for instance, as the chain connection shown having hook ends by which they may be doubled upon themselves and hooked together at the desired point, and also the turn-buckle connections l² for fine but powerful adjustment to give the right traction in accordance with the predetermined requirements and as determined by the scales introduced in the connections.

For exerting traction on the limbs at an upward angle it is only necessary to extend upwardly from the lower rail of the foot portion of the superstructure, one or more verticals M which are adjustably hinged to said lower rail by hinge clamps m corresponding to the clamps k before referred to. The upper rail H in this instance, braces the verticals M against inward swinging movement and in addition the upper end of each may be connected with the side rails H by adjustable connections M' to limit their movement to-

ward the longitudinal center line of the table. The leg tractor device is connected to the vertical M by an adjustable clamp M², said tractor connection also embodying a spring scale m² as in the instances before referred to.

By making each of the elements which go to make up the superstructure adjustable and removable, the table may be adapted for the reception and treatment of patients having almost any bodily deformity and it is especially adapted for the treatment of any deformities susceptible of treatment when the patient is in a reclining position, but it may also be adapted for the treatment of deformities where partial elevation of the body by the tractor devices is necessary or desirable, thus a patient in a sitting position on the table may be treated by shoulder or head traction in a most convenient and thorough manner.

Any one or more of the sections of the superstructure may be removed for the convenience of the patient in reaching position on the table for treatment, or for placing a patient in position when the latter is feeble or helpless.

Having thus described my invention, what I claim as new and desire to secure by Letters Patent, is:

1. A table for orthopedic treatment, comprising a table proper and a superstructure for the attachment of tractor devices, embodying posts and vertically adjustable top and bottom rails carried by said posts; substantially as described.

2. A table for orthopedic treatment, comprising a table proper and a superstructure for the attachment of traction devices, embodying upwardly extending posts, rail clamps vertically adjustable on the posts, rails horizontally adjustable and removably held in the clamps and clamps for tractor connections adjustably mounted on the rails between the posts; substantially as described.

3. A table for orthopedic treatment, comprising a table proper and a superstructure for the attachment of traction devices, embodying posts, horizontal rails adjustable on the posts, verticals adjustably mounted on the rails and means for the attachment of tractor devices carried by the verticals.

4. A table for orthopedic treatment, comprising a table proper and a superstructure for the attachment of traction devices, embodying posts, horizontal rails adjustable on the posts, verticals adjustably mounted on lower rails and resting against upper rails to limit their inward movement and means for the attachment of tractor devices carried by the verticals; substantially as described.

5. A table for orthopedic treatment, comprising a table proper and a superstructure for the attachment of traction devices embodying posts, horizontal rails adjustable on

the posts, clamps for the verticals mounted on the rails, verticals and hinge connections between the verticals and clamps whereby the verticals may be projected at any angle 5 and means carried by the verticals for the attachment of tractor devices.

6. A table for orthopedic treatment, comprising a table proper and a superstructure for the attachment of traction devices embodying posts, horizontal rails adjustably 10

carried by the posts, vertical standards adjustably mounted on the rails, a cross bar connecting said vertical standards and tractor devices suspended from said cross bar; substantially as described.
